UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

VENDING CHART.

Application filed December 8, 1923. Serial No. 679,433.

This invention relates to an improved device in the general nature of a vending chart for facilitating the identification and sale of certain classes of merchandise in retail stores. The device shown in the drawings and hereinafter described relates to curtain fixtures, and the invention has been more especially designed with a view to its use in the retail merchandising of this particular class of articles; but manifestly it may be used with equal advantage to facilitate the merchandising of other articles which are handled in the same general manner.

Manufacturers of curtain fixtures usually put out a considerable line of specifically varying fixtures designed to serve windows of varying widths, as well as single, double, triple and quadruple windows and also employing single, double and triple curtain rods for single and double curtains, valances and overdrapes. In the merchandising of such articles, it has long been the general practice to supply the retail dealer with unit packages from the factory; a unit package being a package containing all of the parts, such as rods, brackets, extension pieces, etc. required for a particular size or character of window; and since the specific requirements of these different sizes and characters of windows and their varying curtain equipments are quite numerous, a large number of different unit packages are required, and the retail dealer is required to carry in stock a large number of each unit package, or else order the same from the factory with undue frequency.

The actual parts going to make up the several unit packages are, to a very large extent, duplicates. For instance, the same end brackets are used on practically all of the different styles and sizes. Extension pieces, used to lengthen the rods, are practically the same in all of the various prescribed lengths of curtain rods. The intermediate supporting brackets are the same in assemblies requiring one, two or more intermediate brackets. Hence, it would naturally prove a great advantage to the retail dealer if, instead of buying a large quantity of the various unit packages, he could buy the parts required to make up the several units in bulk, and then select and combine them as they are called for by his trade. To do this, however, would naturally require an intimate knowledge on the part of

the dealer of the specific make-up of each style of fixture and also an elaborate price-list, from which he could compute the total cost of each specific outfit as ordered. The primary purpose or object of the present invention is to provide, for the use of the retail dealer, a device in the nature of a vending chart or guide, through the manual manipulation of which he can readily ascertain, first the specific parts or equipment required to make up a given order, and secondly the price he should charge for the complete order. The specific equipment required being shown by the chart, the parts can be quickly selected and wrapped up from bulk stock; and the retail price of the assembly being shown by the chart, the salesman is saved the trouble of consulting price lists of the individual parts and totalling them. Another object of the invention is to provide, in such a chart, means for displaying to the customer a picture or cut of the particular equipment he has ordered, with a brief description thereof, so that he can, at a glance, check up on the salesman and see that the latter is properly filling his order.

The retail price of the goods naturally varies from time to time and in different localities. For instance, the cost of the goods at the factory may rise and fall from time to time, and the retail dealer naturally has to vary the retail price accordingly. Again, some dealers are located at or near the factory source with, consequently, little or no freight or express charges to pay on the goods; while others are located at a greater distance, with correspondingly higher freight and express charges, making necessary higher retail prices. My invention, therefore, includes, in its most complete and preferred form, what I may term an adjustable price indicator, which can be set by the individual dealer to show the proper retail price at any given time or in any given locality.

My present invention, its novel structural features, mode of manipulation, and practical advantages to facilitate the retail merchandising of goods that are put out in various sizes and styles and at varying costs will all be readily understood by dealers in this class of merchandise and others skilled in the art to which the invention relates from the following detailed description, taken in connection with the accompanying

drawings wherein I have illustrated one practical embodiment of the invention which has been found in practice to satisfactorily effectuate the stated purposes and objects of the invention, and in which—

5 Fig. 1 is a top plan view, showing my improved vending chart mounted on top of a base or support, the latter also serving as a sample support;

10 Fig. 2 is a top plan view of the rotary disc on which are displayed in the form of sectors the several unit equipments, each sector showing a cut, specifications, brief description, and retail price range;

15 Fig. 3 is a vertical axial section on the line 3—3 of Fig. 1, showing the pointer shifted into the plane of section;

20 Fig. 4 is an enlarged fragmentary vertical section through the central portion of the assembly, more particularly illustrating the mountings of the several concentric parts;

Fig. 5 is a horizontal section on the line 5—5 of Fig. 4;

25 Fig. 6 is a fragmentary top plan view of the stationary cover plate, showing certain openings therein through which indicia on the underlying rotary chart disc are exposed;

30 Figs. 7 and 8 are cross-sectional details on the lines 7—7 and 8—8, respectively, of Fig. 5;

Fig. 9 is a perspective detail of the slide locking cap, and

35 Fig. 10 is a top view of a pivot stud on which the rotary chart disc is mounted.

Referring to the drawings, 10 designates as an entirety a rectangular support for the chart which preferably takes the form of a box having a hinged lid, as indicated in Fig. 1, which box may be further utilized as a container for certain smaller parts of the merchandise, such as the end and intermediate brackets of curtain fixtures in the instance shown. One side of this box may conveniently be utilized as a support for sample specimens of the goods indicated at 11.

50 12 designates as an entirety a circular sheet metal cover plate, the same being formed with a narrow depending rim 13 (Fig. 3) having an outwardly directed annular flange 14 by which it is secured to the lid of the box 10 by screws 15. The plate 55 12 is centrally apertured to receive the hub 16 (Figs. 3 and 4) of an underlying circular rotary chart disc 17 shown in isolated detail in Fig. 2. As herein shown, the lower end of the hub 16 is narrowed to receive the 60 chart disc 17 and the latter is non-rotatably secured thereon by an underlying clamping and stiffening disc 18 and a swaged flange 19 on the lower end of the hub. Preferably, and as shown in Fig. 4, the hub is formed 65 with a central bore, the upper portion of

which is tapped and the lower portion of which is tapered to fit and be centered upon a conical supporting stud 20 that rests upon the upper surface of the main support 10 but is not connected to the latter.

70 On the upper surface of the cover plate 12 are lithographed or otherwise printed a group of radially disposed indicia of the goods, each member of the group, designated as an entirety by 21 preferably comprising a cut or other picture of a complete curtain fixture with printed matter indicating its style and size. At one point in the plate, just inwardly of the periphery thereof, is formed a rectangular opening 22, and diametrically opposite the same are formed a pair of openings 23 and 24 (Fig. 6) in radial alignment, with the narrower opening 23 nearer the center. Between the openings 23 and 24 the metal of the plate is 75 pressed upwardly to form a guide 25 (Fig. 7) for a slide hereinafter referred to which, in co-operation with the price indicating numerals on the underlying chart disc, controls the visible price indications.

79 Referring to Fig. 2, on the upper face of the chart disc 17 are lithographed or otherwise printed a group of radially arranged and generally sector-shaped indicia, each member of the group being designated as an entirety by 26. Each member of the group comprises a group of price indicating numerals designated as a whole by 27 located nearest the center of the disc, printed specifications of the make-up of a particular style of fixture designated as a whole by 28 and located outwardly of the price group 27, and a descriptive group comprising a cut or other picture of the fixture and printed matter descriptive of its style and size designated as a whole by 29 and located near the circumference. It will be observed that the members 27, 28 and 29 of the several sector-shaped groups of indicia make up respectively concentric circular rows, the items in each row being all of the same character. The radial groups 26 on the rotary chart 95 17 correspond in number and subject matter with the radial groups 21 on the cover plate. As shown in Fig. 3 the chart disc 17 is 100 housed within and beneath the cover plate 12, and to facilitate the turning of the disc with a minimum of frictional resistance, said disc has preferably formed thereon near its circumference upwardly and downwardly 105 punched protuberances 30 and 31, the former of which engage with the under side of the cover plate and the latter with the top of the support 10.

110 Referring again to Fig. 1, on the top surface of the cover plate just outwardly of the opening 24 is a printed statement 32 descriptive of the indicia on the chart disc 17 showing through the opening 24; and outwardly of the descriptive matter 32 is addi- 115 120 125 130

tional printed matter designated as an entirety by 33 descriptive of the make-up and additional cost of articles outside the size limits shown and identified on the top of 5 the chart.

Referring more particularly to Fig. 5, 34 designates a flat sheet-metal slide at its outer end engaged with the slideway 25 of the cover plate and having a forked inner end 10 which slidably straddles the upper end portion of the disc hub 16 that projects upwardly through the central aperture of the cover plate 12. In the slide 34 is formed a transversely extending rectangular slot 35 15 of a width sufficient to expose therethrough one of the groups of numerals 27 on the underlying chart disc 17; the slide at the same time concealing from view the other numerals of the group. Between the slot 20 35 and the forked inner end of the slide are formed a group of small slots 36 corresponding in number with the numerals of the group 27 on the chart disc. 37 designates a circular cap having a central aperture 38 25 of a size to fit over the upper end portion of the hub 16 above the forked inner end of the slide 34, and with a narrow annular depending flange 39 that is formed with a transverse notch 40 (Fig. 9) of a width to 30 straddle the shank of the slide 34. Centrally of the notch 40 is a depending locking tongue 41 adapted to interlock with any one of the small notches 36 in the slide 34.

At its extreme upper end the hub 16 is reduced in diameter and given an irregular circumferential shape, as shown at 42 in Fig. 10 to fit a correspondingly shaped hole in the end of a pointer 43; the purpose of the irregular shape of the pointer bearing being 35 to insure that the pointer can be mounted on the post in one position only. The pointer is secured on the upper end of the post by a clamp screw 44 that screws into the tapped bore of the hub 16; and on the base of the 40 pointer are preferably formed a pair of up-standing parallel lugs 45 that may be grasped by the thumb and finger of the operator to turn the pointer and thereby 45 turn the underlying chart disc.

When the pointer is turned the chart disc is rotated beneath the cover plate, and several outer groups 29 on the chart disc are successively brought into a position in which they are visible through the opening 22. At 50 the same time one of the price indicating numerals in the groups 27 is rendered visible through the opening 23 of the cover plate and the narrower opening 35 of the slide bar 34; the particular numeral of each 55 group that is exposed depending upon the position of the slide bar. At the same time also the several equipment describing groups 60 28 of the chart disc are successively exposed through the opening 24 of the cover plate.

65 In the practical use of the device the same

is preferably located on the counter of the retail store with the forward end thereof, which carries the samples 11, toward the front end of the counter and facing the customer. Assuming, for example, that the 70 customer calls for a single curtain rod adjustable from forty-six to seventy-six inches, the salesman swings the pointer 43 to that one of the several radial groups 21 on the cover plate which corresponds to the order. 75 This swings the underlying disc chart to a position wherein there is disclosed through the opening 22, in full view of the customer, the corresponding indicia 29 of the article ordered, thereby showing to the customer 80 that the salesman has correctly understood the order. The same movement brings into view through the opening 24 the description of the equipment necessary to fill the order, comprised in the group 28 on the underlying 85 chart disc; such description appearing in a position to be easily read by the salesman standing behind the counter. The same movement also brings into view of the salesman through the slot 35 of the slide that one 90 of the group 27 of price indicating numerals which gives the retail price of the article ordered. With this information shown by the indicator, the salesman readily picks out from bulk stock parts prescribed at the opening 24, wraps them up and delivers them and receives in return the amount of cash indicated through the opening 35. In this way 95 an order for any of the remaining eleven 100 styles shown is quickly ascertained and filled, and the proper price therefor charged by simply swinging the pointer 43 to the particular style ordered. If an order requiring fixtures shorter or longer than the minimum and maximum lengths shown on 105 the indicator plate is received, the equipment and price of the particular style ordered are determined in the manner already described, and the indicia 33 on the cover 110 plate instruct the salesman with respect to 110 the proper decrease from or increase to the price indicated through the slot 35.

Whenever a change is made in the retail price from one to another of the figures indicated in the groups 27 on the chart disc, the pointer and cap are removed by taking out the screw 44, and the slide 34 is adjusted inwardly or outwardly so as to disclose through its slot 35 the desired new list of prices, and it is locked in its new position by replacing the locking cap with its locking lug 41 engaged with the proper slot 36 of the slide bar. In the device herein disclosed I have shown but three groups of retail price indications; but manifestly the principle may be extended within the radial limits of the device.

The stud 20 shown in Fig. 4 is not necessary to the practical operation of the device, but is preferably employed to afford a solid 130

fitting for the lower end of the hub 16 on the support 10 when making the price indicating adjustments above-described involving the withdrawal and subsequent replacement of the locking cap, pointer and clamp screw, and also to transfer the weight of the rotary chart disc from the cover plate 12 to the foundation support 10.

As I have already indicated in this specification, the device of the present invention possesses marked utility and economy in several important respects. In the first place, it saves the very considerable expense involved in the present practice of putting up the several styles in unit packages, and enables the retail dealer to purchase bulk equipment and himself assemble therefrom the equipment required to fill any particular order. It also tells the salesman at a glance the full equipment required to accurately fill an order for any of the styles indicated on the face of the chart. It also displays to the salesman the correct price to be charged for the order, making it unnecessary for him to search different price lists of the several items making up the complete order and adding them up. It also advises him as to the correct charge for extra and unusual pieces; and, finally, it enables the customer to see at a glance that his order has been correctly understood, and to check up on the salesman's charge.

I have herein shown and described one particular embodiment of the invention which, in practice, has been found to satisfactorily fulfill the stated purposes and objects thereof; but it is manifest that the specific details may be widely varied from those shown both as to subject matter and manner of grouping without involving any departure from the principle of the invention or sacrificing any of the advantages thereof. Hence I reserve all such variations and modifications as fall within the spirit and purview of the appended claims.

I claim—

1. In a vending chart of the character described, the combination of a stationary cover plate formed with three openings at different radial distances from the center thereof, a rotatable disc beneath said cover plate carrying three concentric circular rows of printed items which are successively exposed to view through said openings respectively as said disc is turned, the items in one row being descriptive of different styles of assembled articles of merchandise, the items in another row being definitive of the equipment of said different styles, and the items in the third row indicating the prices of said different styles, and manually operable means for rotating said disc.

2. In a vending chart of the character described, the combination of a centrally apertured stationary cover plate having on its

upper surface a circular row of equally spaced printed items descriptive of different styles of assembled articles of merchandise and formed with three openings at different radial distances from the center of said row, one of said openings being diametrically opposite to the other two, a rotatable disc beneath said cover plate having a hub extending through the aperture of said cover plate and carrying three concentric circular rows of printed items which are successively exposed to view through said openings respectively as said disc is turned, the items in one row being descriptive of the different styles of assembled articles of merchandise shown on said cover plate, the items in another row being definitive of the equipment of said different styles, and the items in the third row indicating the prices of said different styles, manually operable means for rotating said disc, and a pointer on the upper end of said hub; the parts being so co-ordinated that when said pointer is swung to a position indicating any item on said cover plate the corresponding descriptive item on said disc will show through one of said openings and the equipment and price indicating items on said disc pertaining thereto will show through the other two openings diametrically opposite to said last named opening.

3. In a vending chart of the character described, the combination of a stationary cover plate formed with an opening, a disc beneath said cover plate mounted to turn on an axis eccentric to said opening and having on its upper side a plurality of groups of radially arranged price-indicating items so located as to pass successively beneath said opening as said disc is turned, means associated with said opening and adjustable to cover different parts thereof whereby only items of the several groups which are at equal distances from the axis of the disc are rendered visible through said opening, and means for locking said cover means in adjusted position.

4. In a vending chart of the character described, the combination of a stationary cover plate formed with an opening eccentrically thereof, a rotatable disc beneath and concentric with said cover plate carrying a plurality of concentric circular rows of price-indicating numerals, individual numerals of the several rows being arranged in radial groups which pass successively beneath said opening as said disc is turned, an adjustable cover for said opening itself formed with an opening of a size to expose but one numeral of each radial group, and means for securing said cover in adjusted position.

5. In a vending chart of the character described, the combination of a stationary cover plate formed with an opening eccen-

- trically thereof, a rotatable disc beneath and concentric with said cover plate carrying a plurality of concentric circular rows of price-indicating numerals, individual numerals of the several rows being arranged in radial groups which pass successively beneath said opening as said disc is turned, a slideway on said cover plate, a radial slide engaged with said slideway and overlying 10 said opening, said slide itself formed with an opening of a size to expose but one numeral of each radial group, and means for locking said slide in adjusted position.
6. In a vending chart of the character described, the combination of a centrally apertured stationary cover plate formed with an opening eccentrically thereof and with a slideway adjacent to said opening, a rotatable disc beneath said cover plate having a 15 hub extending through said opening and carrying a plurality of concentric circular rows of price-indicating numerals, individual numerals of the several rows being arranged in radial groups which pass successively beneath said opening as said disc is turned, a slide having a forked inner end straddling the upper end of said hub and at its outer end engaged with said slideway, said slide formed with an opening of a size 20 to expose but one numeral of each radial group, and means for locking said slide in endwise adjusted position.
7. In a vending chart of the character described, the combination of a centrally apertured stationary cover plate formed with an opening eccentrically thereof and with a slideway radially beyond said opening, a rotatable disc beneath said cover plate having a hub extending through said opening 25 and carrying a plurality of concentric circular rows of price-indicating numerals, individual numerals of the several rows being arranged in radial groups which pass successively beneath said opening as said disc is turned, a slide having a forked inner end straddling the upper end of said hub, a plu- 30 rality of apertures spaced lengthwise thereof, and at its outer end engaged with said slideway, said slide formed with an opening of a size to expose but one numeral of each radial group, and a cap removably mounted on the upper end of said hub and formed with a locking lug engageable with any of said apertures in said slide whereby to lock the latter in endwise adjusted position. 35
8. In a vending chart of the character described, the combination of a flat base plate, a shallow sheet-metal cover plate formed with a circumferential flange detachably secured to said base plate, said cover plate having a central aperture and an eccentrically disposed opening, and a flat sheet-metal disc beneath said cover plate having a hub journaled in the central aperture of the latter, and having on its upper side a circular row of printed indicia successively visible through said opening of the cover plate as said disc is turned, said disc also formed with upwardly and downwardly pressed lugs in sliding engagement with the under surface of said cover plate and the top surface of said base plate, respectively, as said disc is turned. 40
9. In a vending chart of the character described, the combination of a cover plate formed with an opening, a movable chart plate beneath said cover plate having thereon a plurality of parallel rows of printed items, said rows indicating respectively different prices of various articles of merchandise indicated on the chart, laterally adjacent items in the several rows passing successively into register with said opening as said chart plate is moved, and a slide covering said opening and itself formed with an opening of a width substantially equal to one of said rows, whereby only items of one of said rows are visible through said opening in any set position of said slide. 45

JAMES H. BOYE.
